[57] CLAIM

The ornamental design for a toy aircraft, substantially as
shown and described.

DESCRIPTION

FIG. 1 is a perspective view of a toy aircraft showing
our new design;

FIG. 2 is a top plan view thereof;

FIG. 3 is a side elevational view thereof, the side oppo-
site being substantially a mirror image thereof;

FIG. 4 is a bottom plan view thereof;

FIG. 5 is a front elevational view thereof; and

FIG. 6 is a rear elevational view thereof.

FIG. 1

FIG. 2

FIG. 5

FIG. 4

FIG. 5

FIG. 6
